ATTORNEY.

UNITED STATES PATENT OFFICE.

JOHN F. HUTCHINGS, OF EATON, INDIANA.

IMPLEMENT FOR DEPOSITING CORES.

Application filed October 15, 1925. Serial No. 62,554.

To all whom it may concern:

Be it known that I, JOHN F. HUTCHINGS, a citizen of the United States, residing at Eaton, in the county of Delaware and State of Indiana, have invented new and useful Improvements in Implements for Depositing Cores, and of which said invention the following is a specification.

This invention relates to improvements in devices for forming molds for the casting of sash-weights.

A method heretofore used for preparing molds of the class referred to, involves the use of a bottom plate with upstanding projections which are intended to form the eye of the mold, a flask, and a templet plate placed on top of the flask, and through which said plate the vertically disposed cylindrical patterns are plunged to lowered position in the loose sand. After the sand has been rammed to a depth sufficient to hold the patterns firmly in position, the templet plate is removed, and then additional sand is rammed to form the top portion of the mold. A second flask is then placed on top of the main flask and is rammed with sand and provided with runners or gates adapted to receive the molten metal.

Another known method, consists of placing a templet plate on the surface of the sand in the flask and forming a central basin and radial gates therefrom, passing a plurality of patterns having tapered ends through the apertures in said templet plate and plunging them into the sand a suitable depth, then withdrawing said patterns and removing the templet plate, and finally, the positioning of cores in the molds to form the sash-weight eyes.

The sash-weight of form made in molds of the class above referred to has become standard, and consists simply of a cylindrical casting about one and three quarters of an inch in diameter, and of length to accord with the heaviness desired, the end of the casting being provided with an eye.

I am aware that a sash weight of the same formation as that just described, has been produced in the standard type of mold consisting of the cope and drag flask, and the match plate, the parting line being lengthwise of the casting. This form of mold, however, even though not requiring a core, does not lend itself to quantity production,

as does the mold of the vertical or plunger type.

The general object of the present invention is to render practicable more rapid and economical construction of sash-weights by means of molds of the vertical type hereinbefore referred to, and to minimize the amount of work and labor necessary to make such mold or molds in readiness for receiving the molten metal. Accordingly, the invention contemplates the providing of an implement for depositing a core in the mold, such implement consisting of a hollow or open body member capable of being projected into and retracted from the mold, there being a central recess in its lower end, a grip device carried by said body member, adapted to retain and hold the core while it is being lowered to and deposited in position in the eye portion of the mold, and then to release its hold.

A practicable form of embodiment of my invention is shown in, and the objects of the invention are accomplished by the new construction, combination and arrangement of parts illustrated in the accompanying drawings, and described in the following specification.

The several parts of the invention are identified by suitable characters of reference applied thereto in the different views, in the drawings, in which—

Figure 1 is a vertical central sectional view of my improved implement, the grip device being shown retained by the holder means, at the normally expanded or open position.

Figure 2 is a view similar to Figure 1, the holder means having been moved, thus permitting the grip device to become retracted.

Figure 3 is a top plan view of Figure 1.

Figure 4 is a top plan view of Figure 2.

Figure 5 is a side view of the lower portion of the hollow column or body member.

Figure 6 is a view of Figure 5 as seen in the direction indicated by arrow 6 in Figure 5, the core being shown.

Figure 7 is a side view of a core of the form desired for forming the eye in the casting.

Figure 8 is an end view of Figure 7.

Figure 9 is a cross section view of line 9—9 in Figure 6,

105

Figure 10 is a sectional view of a portion of a flask and its sand contents, in which a mold has been formed, the core having been deposited by the implement herein described.

The body member of my improved implement consists of a cylindrical hollow column A which may be of light cast metal or of sheet metal. It is of diameter slightly less than that of the mold 1 so that it may be easily projected into and withdrawn from the mold, and is of such length that when at the lowered position, the upper portion of the column extends above the surface of the sand. The lower portion or nose of the column is of tapered formation and has the faces A¹ and A² to register with the walls 1^a and 1^a of the bottom of the mold. The width of the nose between the faces A¹ and A² is such as to provide a clearance between said walls 1^a and 1^a, for the purpose presently to be mentioned.

The baked sand core 2, as shown in Figure 7, is circular in cross section, and has the flanges 2^a and 2^a. These flanges become seated in engagement with the beveled seats A³ and A⁴, and the end faces are adapted to directly engage the slightly slanted walls 1^a of the mold.

A longitudinal rib A² on the side of the column A is adapted to find engagement with a complementary groove or channel 3 in the side of the mold, whereby the disposing of the implement at true position so that the nose of same is in alignment with the bottom portion of the mold, is facilitated. In molds of the type where the bottoms are plain, as distinguished from a mold of the kind shown for the casting having tapered nose, the guide ribs above referred to are not present, it being understood of course that in molds having plain bottoms, the nose portion of the implement is of modified form accordingly.

Jaw pieces D and D which are journaled on a cross pin E have the arms F and F. Links G and G connected loosely to the ends of said arms, have their ends journaled on a cross pin H.

A helical spring I has its lower end connected to said cross pin H, and its upper end is connected to a lug J that is secured to the wall of the column. Push rod K which is passed through a suitable aperture therefor, in the head piece L of the column, has its lower end connected to the cross pin H. The outer portion of the push rod is extended a suitable distance beyond said head piece and has the angular portion or head K¹, and the handle K². The function of the spring I is to urge the jaws toward each other. The function of the push rod is to actuate the grip device, thereby causing the jaws to be moved apart, or away from each other.

A holder member whose function is to hold the push bar at the pushed-in position, consists of a rod M which is journaled in the head piece L and retained by collars M¹. When at the holding position, the arm M² of said holder member is in engagement with the head K¹ of the push rod.

Centrally of the tapered or bottom portion of the column is a slot or transverse opening A⁴ which is of dimensions to easily receive the core piece, the angular marginal portions A⁵ of said opening providing space for the flanges of the core piece, so that same may be easily inserted in the said opening.

The invention in readiness to operate, appears as shown in Figure 1. In the view Figure 10, one of the several molds 1 which have been prepared, is shown in cross section. It will be understood that means of suitable form (not shown) for raising and lowering the patterns in multiple arrangement, are provided, and also that a quantity of cores are available for being positioned in the molds.

To practice the invention, the operative disposes the implement with its recess in engagement with a core, as shown in Figure 1; then by a shift of the handle M² the holder member becomes disengaged from the push rod, thus releasing the latter. The action of the spring I causes jaws D and D to move toward each other and to enwrap the core, thereby holding it firmly in the said recess or opening A⁴. The implement is then disposed within the mold, the rib A² being in engagement with the groove 3 of the latter, thus assuring the correct entry by the tapered portion of the implement, into the similar tapered portion of the mold. The length of the core is such that when the implement will have reached its destination, the core will have become wedged into engagement with the side walls 1^a of the mold sufficiently securely for the purpose of forming the eye when the molten metal is filled into the mold. The operative then depresses the handle K¹ and returns the handle M² to normal engagement with the head portion of the push rod, the effect of such manipulation being to move the jaws to, and to retain the jaws in the expanded or open position, and disengaged from the said core. The operative then simply withdraws the implement from the mold, and repeats the above practice for the next mold.

By reason of the simplicity of the operation of this device, and of the elimination thereby of the use of cores of complicated form, and possible extra or additional flasks, it is possible to make ready the molds, with rapidity. While it is possible that there may be slight variation in the smoothness of the casting at the eye portion of the mold, due to an inconsiderate serration of the wall of the mold,

at the location where the core is impinged, this is not objectionable and constitutes no impairment of the product.

While I have shown this invention as applicable to the depositing of a core in a mold intended solely for a sash-weight, it is understood that the invention is applicable in connection with the production of castings of all forms capable of being formed in the 10 plunger type of vertical mold described. Also it will be understood that modifications may be made in the details of construction, of the combination and arrangement of parts of my invention, without departing from its 15 spirit or principles.

What I claim as my invention, and desire to secure by Letters Patent of the United States, is—

1. An implement for depositing cores in 20 molds, comprising a hollow column adapted to be projected into the mold and having bifurcate lower end adapted to embrace a core, a grip device having a jaw on each side of the bifurcation, means to urge the jaws 25 closed, means to retain the jaws normally open, and operable to permit the jaws to close.

2. An implement for depositing cores in 30 molds, comprising a body member adapted to be projected into the mold and having a slot in its end to embrace a core, a grip device having a jaw on each side of the slot, means to yieldingly urge the jaws closed, means to retain the jaws normally open and 35 operable to permit the jaws to close.

3. An implement for depositing cores in 40 molds, comprising a hollow column adapted to be projected into the mold and having an opening in its end to embrace a core, a grip device in the column having a jaw on each side of said opening, means to yieldingly urge the jaws closed, a push rod to move the jaws to open position, and a holder member to hold the push rod at the pushed-in 45 position.

4. An implement for depositing cores in 50 molds, comprising a hollow body member adapted to be projected into the mold and having an opening in its end to embrace a core, a grip device in said body member having a jaw on each side of the said opening, a spring to urge the jaws toward each other, an opener member operable to resist the spring and move the jaws apart, and a holder member to hold the opener member at the 55 operated position.

5. An implement for depositing cores in 60 molds, comprising a hollow column adapted to be projected into the mold and having an opening in its end adapted to embrace a core, a grip device in the column having a jaw on each side of the column, a push rod loose in and projected from the column and having connection with the grip device so that when pushed the grip device operates 65 to move the jaws apart, and a holder means on the column operable to engage and hold the push rod at the pushed-in position.

JOHN F. HUTCHINGS.
